UNITED STATES PATENT OFFICE.

GEORGE F. HUTCHINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-BOX MOTION FOR LOOMS.

SPECIFICATION forming part of Letters Patent No. 787,448, dated April 18, 1905.

Application filed April 14, 1904. Serial No. 203,086.

To all whom it may concern:

Be it known that I, GEORGE F. HUTCHINS, a citizen of the United States, residing at Worcester, in the county of Worcester and State of Massachusetts, have invented new and useful Improvements in Shuttle-Box Motions for Looms, of which the following is a specification.

My invention relates to the shuttle-box motion of a loom, and particularly to that class of shuttle-box motions in which the vertical movement of two or more shuttle-boxes at one or both ends of the loom is controlled by a pattern-indicating mechanism.

The object of my invention is to improve upon the construction of shuttle-box motions of different types as ordinarily made, and more particularly to provide in a set of connections intermediate a lever operated by the pattern-chain surface and the movable shuttle-boxes at one or both ends of a loom two cranks, the first crank—the one nearer the pattern-surface, which in this instance is the well-known vibrator-gear—driving or moving and locking in position the other or second crank nearer the boxes and each crank at every movement thereof moving from one extreme position to its other extreme position or its full throw through an arc of substantially one hundred and eighty degrees. By means of the two cranks in the set of connections between a lever operated by the pattern-surface and the shuttle-boxes I obtain a double-crank motion, or one crank compounded on the other, to move the shuttle-boxes from one cell to another and obtain a very quick movement of the shuttle-boxes while the two cranks are passing their middle positions and a very slow and easy movement of the shuttle-boxes when starting and stopping.

I may use in connection with my improvements in shuttle-box motions a multiplier mechanism of any well-known construction and operation for repeating certain bars of the box pattern-chain in any well-known way.

My invention consists in certain novel features of construction of my improvements, as will be hereinafter fully described.

I have only shown in the drawings sufficient portions of a loom and the shuttle-box motion and a multiplier mechanism with my improvements applied thereto to enable those skilled in the art to understand the construction and operation thereof.

Referring to the drawings, Figure 1 is a rear view of a loom-frame and shuttle-box indicating mechanism embodying my improvements. Fig. 2 is a sectional end view of the parts shown in Fig. 1, taken at a point indicated by line 2 2, Fig. 1, looking in the direction of arrow *a*, same figure. Some of the parts shown in Fig. 1 are not shown in this figure. Fig. 3 shows, on an enlarged scale, a side view of the give-way mechanism for the shuttle-box rod looking in the direction of arrow *b*, Fig. 4. Fig. 4 is an edge view of the parts shown in Fig. 3 looking in the direction of arrow *c*, same figure. Fig. 5 shows a modified construction of the rack-and-pinion mechanism shown in Fig. 2. Fig. 6 shows, on an enlarged scale, the head portion of the loom shown at the left in Fig. 1 detached, with some additional parts. Fig. 7 is a rear view of a multiplier mechanism detached, combined with the box pattern-chain mechanism. Fig. 8 is a sectional view on line 8 8, Fig. 7, looking in the direction of arrow *d*, same figure.

I will now describe my improvements, which I have shown in this instance combined with four movable shuttle-boxes at each end of the loom.

In the accompanying drawings, 1 represents the loom sides, and 2 the loom-arches.

In Fig. 1 of the drawings is shown a part of the "Knowles" box indicating mechanism shown and described in United States Re-issue Letters Patent No. 7,784 and comprising the upper box cylinder-gear 4, the lower box cylinder-gear 5, the vibrator-levers 6, extending over and actuated by the pattern-chain 7 on the pattern barrel or cylinder 7' on the shaft 7", which shaft also carries the pattern-chain (not shown) of the harness-motion, the vibrator-gears 8, carried on the levers 6 and forming cranks which at each movement

from one extreme position to the other move through an arc of substantially one hundred and eighty degrees in the usual way, and the vibrator-connectors 9.

5 The two vibrator-connectors 9 are pivotally connected to the two levers or arms 10 and 10'. The lever 10 has a hub 10", loosely mounted on a shaft 11. The lever 10' has a hub 10", fast on the shaft 11 to cause said shaft to rock 10 with said lever 10'.

The four movable shuttle-boxes 13 at the left-hand end of the loom in Fig. 1 are supported on the upper end of a vertically-moving rod 14 and guided in the box-frame in the usual way. The rod 14 is adjustably secured in this instance at its lower end in a boss 15 on a stud 16, held in a give-way connection. The give-way connection 17 in this instance consists of an upright part 17', having a curved 15 recess portion near its middle portion to receive the stud 16 and forked at its lower end 17" (see Figs. 1 and 4) to receive the end of the box-lever 18, which is pivotally attached thereto. The part 17' of the give-way connection 17 has a boss 17^a at its lower end for the box guide-rod 19 and also a boss 17^b at its central portion for the guide-rod 19. The box guide-rod 19 is attached at its lower end to the rocker-iron 20 of the lay-sword 21 in the usual way and at its upper end to the box bearing or casing 22. (See Fig. 2.) The other part, 17", of the give-way connection 17 is pivotally attached at its lower end to the part 17' and has a curved recessed portion at about its middle portion to receive the stud 16 on the boss 15.

The upper end of the part 17" is connected to the part 17', and the two parts are yieldingly held together to hold the stud 16 and 40 cause the box-rod 14 to move up and down with the give-way connection, in this instance by a spiral spring 23, which is attached at one end to the part 17" and at its other end to a latch 24, pivoted on the part 17'. (See Figs. 45 2 and 3.)

When the latch 24 is in its normal position, the tension of the spring 23 acts to hold the parts 17' and 17" of the give-way connection 17 together; but when the latch 24 is moved 50 down, as shown in dotted lines, Fig. 3, the tension of the spring 23 is released to allow of the parts 17' and 17" of the give-way connection 17 being moved apart to disengage the stud 17. Two springs 23 may be used, 55 if preferred, one on each side of the latch 24.

The collar 15, carrying the stud 16, is preferably loosely mounted on the lower end of the box-rod 14, and by means of the two nuts 15' on the threaded end of the rod, one above 60 and one below the collar 15, said collar may be adjusted up or down on the rod 14 and secured thereon to properly position the shuttle-boxes as desired. A spring 14", (see Fig. 1,) attached at one end to a stationary part 65 (not shown) and at its other end to a flexible

connection 14", which passes over a pulley 14'" and is attached to the give-way connection 17, acts as a counterbalance to the weight of the shuttle-boxes.

The box-lever 18, as before stated, is pivotally attached at one end to the lower end of the part 17' of the give-way connection 17, and at its other end is pivotally attached to the lower end of a connector 25. The upper end of said connector 25 is pivotally attached 75 to a crank 26, fast on one end of a shaft 27, mounted in bearings on a stand 28 on the loom-frame. On the opposite end of the shaft 27 is fast a pinion 29, which meshes with the teeth 30' on the lower end of a vertically-moving rod 30, the upper end of which is pivotally connected with a lever or arm 31, fast on the hub 10" of the lever 10.

The box-lever 18 intermediate its ends has the lower end of a connector 32 pivotally attached thereto, (see Fig. 2,) forming a movable fulcrum for the lever 18. The upper end of the connector 32 is pivotally attached to a crank 33, fast on one end of a shaft 34, mounted in bearings on the loom-frame. On 90 the opposite end of the shaft 34 is fast a pinion 35, which meshes with the teeth 36' on a vertically-moving rod 36, the upper end of which is pivotally connected with a lever or arm 37, having a hub 27 fast on the shaft 11. 95

A roll 38, mounted on a stud 38 on the frame 1, is located directly back of the toothed portion of the rods 30 and 36 to hold them in mesh with the pinions 29 and 35, as shown in Fig. 2.

100 I have described one box-lever 18 and its operating mechanism and parts connected therewith, which forms a complete box-motion for one set of shuttle-boxes at one end of the loom entirely independent of the box-motion for the shuttle-boxes at the other end of the loom.

The several parts of the box-motion for the shuttle-boxes at the other or right-hand end of the loom (shown in Fig. 1) correspond to 110 and are of the same construction and operation as the parts of the box-motion already described and shown at the left-hand end of the loom in Fig. 1 and are designated by the same letters of reference with the letter "a" 115 added thereto.

In order to connect the box-motion on the right-hand end of the loom with the vibrator-gears 8 of the pattern-indicating mechanism on the left-hand end of the loom at the upper 120 part thereof, two long rigid connectors 9^a are used, which extend back of the arch 2. (See Fig. 1.)

The operation of my improvements will be 125 readily understood by those skilled in the art.

In Fig. 5 I have shown a modified construction of the pinions 29 and 35 and toothed portions of the rods 30 and 36. The pinions 29^b and 35^b are eccentric, and the toothed portions 30^b and 36^b are in this instance made in 130

the arc of a circle to allow of the revolution of the eccentric pinions, with the toothed portions 30^b and 36^b held in engagement therewith by the rolls 38^b. By means of the eccentric pinions 29^b and 35^b I obtain a fast and slow motion of the lever 18.

In Fig. 6, in addition to the parts shown in Fig. 1, I have shown some of the parts of the multiplier mechanism shown in Figs. 7 and 8, which is of well-known construction and fully shown and described in United States Letters Patent No. 413,369, of October 22, 1889, to which reference is made. In said Figs. 6, 7, and 8, 38^a is the auxiliary pattern-chain bar 15 rel of the box mechanism, mounted on the shaft 7" and carrying the auxiliary pattern-chain 39^a. A lever 40, pivoted at one end at the upper end of a stand 41, extends over the auxiliary pattern-chain 39^a and has pivotally 20 attached at its outer end the upper end of a link 42. The lower end of the link 42 is connected with one arm of a bell-crank lever 43, pivoted at 44. The other arm of the bell-crank lever 43 engages with a collar 45, fast 25 on a rod 46, carrying a yoke 47, which engages the hub of a pin-wheel 48, adapted to slide on a rod 49 and move into and out of engagement with a star-wheel 50, fast on a sleeve carrying the box pattern-barrel 7. A 30 second star-wheel 51 is operated by a pin-wheel 52, which is adapted to slide on the rod 49 and be moved out of engagement with the star-wheel 51 by a yoke 53 engaging the hub of said pin-wheel 52. Said yoke 53 is fast on 35 a rod 54. Also fast on the rod 54 is a collar 55, having a notch therein to receive the end of one arm of an angle-lever 56, pivoted at 57. The other arm of said angle-lever 56 is connected by a link 58 with an indicator-lever 59, 40 pivoted at 60 on a stand 61. The indicator-lever 59 extends over a series of indicators 45 on the box pattern-chain 7 and is controlled thereby.

To an extension 43' on the angle-lever 43 is attached a spring 62, which acts to move the angle-lever 43 on its pivotal support, and through collar 45, sliding rod 46, and yoke 47 move the pin-wheel 48 out of engagement with the star-wheel 50. A spring 63 is attached to an extension 56' on the angle-lever 56 and acts to move the angle-lever 56 on its pivotal support and through the collar 55 and rod 54 and yoke 53 move the pin-wheel 52 out of engagement with the star-wheel 51, all in 55 the usual and well-known way.

The operation of my improvements will be readily understood by those skilled in the art.

I provide in each set of connections between a single lever operated by the pattern-surface 60 and the shuttle-boxes two cranks. The first crank, as above mentioned, being the vibrator-gear 8 and receiving its motion from the driving-cylinders 4 and 5, is moved through an arc of substantially one hundred and eighty 65 degrees in the usual manner and locked at its

dead-center with respect to its connector 9. Through the movement of the first crank or vibrator-gear 8, connector 9, angle-lever 10, having an arm 31, and connector 30, said connector 30 having a toothed section thereon, 30', adapted to mesh with and rotate a pinion 29, fast on shaft 27, the crank 26, fast on said shaft 27, is also positively rotated or moved through an arc of a circle of substantially one hundred and eighty degrees at each movement of the vibrator-gear 8, thereby moving, through a connector 25 and lever 18, the giveaway mechanism and shuttle-boxes through a lift of one cell. The two connector-pins of the connector 25 are held in substantial alinement with the center of shaft 27, the second crank 26 being at what is termed its "dead-center" with respect to its connector 25. In case of the desired movement of the shuttle-boxes for more than a single cell then the movement of the second vibrator 75 gear or crank 8, through its connections with box-lever 18, between the end thereof and the giveaway mechanism, in a similar way, as above described, will compound the movement of said lever 18 to move the shuttle-boxes 13 80 for more than a single cell, as will be understood. A similar and independent movement of the shuttle-boxes at the other end of the loom may be obtained through the vibrator-gears 8, rigid connectors 9^a, and cranks and 85 connectors, as before described.

I wish it to be clearly understood that in my construction any weight or strain that may come on the boxes after the full movement of the vibrator-gear 8 is accomplished will 90 come directly on the second cranks 26 and 33, shafts 27 and 34, thereby relieving the vibrator-gears 8 of any strain after the full movement thereof. The second cranks are held in their locked or dead-center positions by the 105 vibrator-gears 8.

A box-motion of any number of cells may be obtained by the substitution of as many compound levers for the lever 18 as may be required, together with additional sets of 110 cranks and connectors. Each set of connections between the pattern-chain indicator-lever and its corresponding compound lever has therein two cranks, giving a double-crank motion in each set of connections, as before described.

I have shown herein and particularly described my improvements combined with what is ordinarily termed the "Knowles" box indicating mechanism; but it will be understood 120 that my improvements may be adapted to be applied to looms of ordinary construction provided with any well-known box indicating mechanism having two or more movable shuttle-boxes at one or both ends of the loom, and 125 my improvements may be used in connection with any ordinary box-motion multiplier mechanism, as the one shown in the drawings, if desired.

It will be understood that the details of con- 130

struction of my improvements may be varied, if desired, and particularly the arrangement of the connections intermediate the lever moved by the pattern-surface and the shuttle-boxes and the location of the two cranks in each set of connections.

Having thus described my invention, what I claim as new, and desire to secure by Letters Patent, is—

- 10. 1. In a box-motion of a loom, the combination with a lever moved by the pattern-surface, and the shuttle-boxes, of connections intermediate said lever and the shuttle-boxes, said connections having therein two cranks, each crank, at each movement thereof, moving through an arc of substantially one hundred and eighty degrees, substantially as shown and described. 70
- 20. 2. In a box-motion of a loom, the combination with a lever moved by the pattern-surface, and the shuttle-box lifting or vertically moving rod, of connections intermediate said lever and said rod, said connections having therein two cranks, one moving the other, through intermediate connections, and each crank, at each movement thereof, moving through an arc of substantially one hundred and eighty degrees, substantially as shown and described. 80
- 25. 3. In a box-motion of a loom, the combination with a lever moved by the pattern-surface, and the shuttle-boxes, of rigid or non-flexible connections, intermediate said lever and the shuttle-boxes, said connections having therein two cranks, to cause a shuttle-box to be moved from one position to another by a double-crank motion, and each crank, at each movement thereof, moving through an arc of substantially one hundred and eighty degrees, substantially as shown and described. 85
- 30. 4. In a box-motion of a loom, the combination with levers moved by the pattern-surface, and shuttle-boxes at each end of the loom, of connections intermediate said levers and said shuttle-boxes, each set of connections having therein two cranks, and each crank, at each movement thereof, moving through an arc of substantially one hundred and eighty degrees, substantially as shown and described. 90
- 40. 5. In a loom having movable shuttle-boxes at each end, the combination with the box pattern-surface, of connections therefrom to the shuttle-boxes at each end of the loom, each set of connections, intermediate a lever moved by the pattern-surface and the shuttle-boxes at each end of the loom, having therein two cranks, to cause a shuttle-box to be moved from one position to another by a double-crank motion, and each crank, at each movement thereof, moving through an arc of substantially one hundred and eighty degrees, substantially as shown and described. 95
- 50. 6. In a loom having movable shuttle-boxes at each end, the combination with the box pattern-surface, located at one end of the loom, of rigid or non-flexible connections therefrom to the shuttle-boxes at each end of the loom, each set of connections having therein two cranks, one moving the other, through intermediate connections to obtain a double-crank motion for each shuttle-box, and each crank, at each movement thereof, moving through an arc of substantially one hundred and eighty degrees, substantially as shown and described. 100
- 60. 7. In a loom, the combination with an upper cylinder-gear, and a lower cylinder-gear, vibrator-levers, vibrator gears or cranks, and one or more vibrator-connectors, of connections from said connectors to the shuttle-boxes, on one end of the loom, each set of connections having therein a crank, which, at each movement thereof, moves through an arc of substantially one hundred and eighty degrees, and one or more vibrator-connectors extending across the loom, and connections therefrom to the shuttle-boxes on the other end of the loom, each set of connections having therein a crank, which, at each movement thereof, moves through an arc of substantially one hundred and eighty degrees. 105
- 70. 8. In a loom, the combination with the upper cylinder-gear, and the lower cylinder-gear, vibrator-levers, vibrator-gears, and one or more vibrator-connectors, of rigid or non-flexible connections therefrom to the shuttle-boxes on one end of the loom, and one or more vibrator-connectors extending across the loom, and rigid or non-flexible connections therefrom to the shuttle-boxes on the other end of the loom, substantially as shown and described. 110
- 80. 9. In a loom, the combination with movable shuttle-boxes, a shuttle-box rod, a give-way connection adjustably attached thereto, a shuttle-box lever, and a vibrator-connector, of rigid or non-flexible connections intermediate said box-lever and said vibrator-connector, said connections comprising a connector, a crank, a shaft or stud, a pinion thereon, a tooth-rod meshing with said pinion and connected with a lever, and said lever mounted on a shaft, and said shaft, and a second lever connected with said vibrator-connector, substantially as shown and described. 115
- 90. 10. In a loom, the combination with movable shuttle-boxes, a shuttle-box rod, a give-way connection adjustably attached thereto, a shuttle-box lever, and a vibrator-connector, of rigid or non-flexible connections intermediate said box-lever and said vibrator-connector, said connections comprising a connector, a crank, a shaft or stud, an eccentric pinion thereon, a rod having a toothed portion meshing with said pinion and connected with a lever, and said lever mounted on a shaft, and said shaft, and a second lever connected with said vibrator-connector, substantially as shown and described. 120
- 100. 11. In a loom, the combination with the shuttle-boxes, and the shuttle-box rod, of a 125
- 110. 12. In a loom, the combination with the shuttle-boxes, and the shuttle-box rod, of a 130

collar adjustably mounted on said rod, a stud on said collar to be held in a give-way mechanism, and said give-way mechanism, and a flexible connection from said give-way connection to a counterbalance-spring, and said counterbalance-spring, substantially as shown and described.

12. In a loom, the combination with movable shuttle-boxes, a shuttle-box rod adjustably held in a collar, and said collar having a stud thereon, of a give-way mechanism comprising two parts recessed to receive the stud on the collar, and one part pivoted to the other, and said parts held together by a spring, and said spring, and a latch connected with said spring to release the tension thereof, substantially as shown and described.

13. In a box-motion of a loom, the combination with a lever moved by the pattern-surface, and the shuttle-boxes, and connections intermediate said lever and the shuttle-boxes, said connections having therein two cranks, each crank, at each movement thereof, moving through an arc of substantially one hundred and eighty degrees, of a box-motion multiplier mechanism, substantially as shown and described.

14. In a box-motion of a loom, the combination with a lever moved by the pattern-surface, and movable shuttle-boxes at one end of the loom, of connections intermediate said lever and said shuttle-boxes, said connections having therein two cranks, each crank, at each movement thereof, moving through an arc of substantially one hundred and eighty degrees, substantially as shown and described.

15. In a box-motion of a loom, the combination with levers moved by the pattern-surface, and movable shuttle-boxes at one end of the loom, of connections intermediate said levers and said shuttle-boxes, each set of connections intermediate a lever and the shuttle-boxes, having therein two cranks, each crank, at each movement thereof, moving through an arc of substantially one hundred and eighty degrees, substantially as shown and described.

16. In a box-motion of a loom, the combination with levers moved by the pattern-surface,

and movable shuttle-boxes at each end of the loom, of connections intermediate said levers and said shuttle-boxes, each set of connections intermediate a lever and the shuttle-boxes, having therein two cranks, each crank, at each movement thereof, moving through an arc of substantially one hundred and eighty degrees, substantially as shown and described.

17. In a loom having movable shuttle-boxes at each end of the loom, and a shuttle-box lever or levers at each end of the loom, the combination with the box pattern-surface, located at one end of the loom, of connections therefrom to the shuttle-boxes at each end of the loom, each set of connections having therein two cranks, each crank, at each movement thereof, moving through an arc of substantially one hundred and eighty degrees, substantially as shown and described.

18. In a loom, having movable shuttle-boxes at each end of the loom, and a shuttle-box lever or levers, the combination with the box pattern-surface located at one end of the loom, of connections therefrom to the shuttle-boxes at each end of the loom, each set of connections having therein two cranks, each crank, at each movement thereof, moving through an arc of substantially one hundred and eighty degrees, and the two cranks in each set of connections to the movable shuttle-boxes on the box-pattern-surface end of the loom, being at said end of the loom, and one of the two cranks in each set of connections to the shuttle-boxes at the other end of the loom, being located on the box-pattern-surface end of the loom, and the other on the opposite end of the loom, substantially as shown and described.

19. In the shuttle-box motion of a loom, the combination with the shuttle-boxes, and a vibrator gear or crank, of a second crank, and connections intermediate said vibrator-gear and said second crank, said connections having therein gear-teeth or toothed surfaces, substantially as shown and described.

GEORGE F. HUTCHINS.
